UNITED STATES PATENT OFFICE.

DAVID A. KENT, OF JEWELL, IOWA.

NECK-PROTECTOR FOR DRAFT-ANIMALS.

1,056,342.

Specification of Letters Patent. Patented Mar. 18, 1913.

Application filed March 6, 1911. Serial No. 612,671.

To all whom it may concern:

Be it known that I, DAVID A. KENT, a citizen of the United States, residing at Jewell, in the county of Hamilton and State 5 of Iowa, have invented a certain new and useful Neck-Protector for Draft-Animals, of which the following is a specification.

The object of my invention is to provide a neck protector for draft animals which prevents all lateral friction of the harness or 10 collar on the neck.

Many neck pads have been made heretofore, but all such pads which are secured to the collar move therewith and rub the neck.

15 Pads which have been made to be used independent of the collar and not secured thereto, are subject to the objection that they have been likely to slip out from under the collar permitting the collar to rub on the neck.

20 Another object of my invention is to provide a neck protector of such form and construction that it will always fit in its proper place under the collar and that it will not slip forward or backward when the collar is 25 in position. In other pads the downward draft presses upon a small area upon the top of the neck, causing soreness.

Another object of my invention is to provide such a device whereby the downward 30 draft is distributed over a comparatively large area.

35 Another object of my invention is to provide a neck protector which serves as a pad and also as a housing to keep out water or the like.

40 My invention consists in certain details, in the construction, arrangement and combination of the various parts of the device, whereby the objects contemplated are attained, as hereinafter set forth, pointed out in my claim and illustrated in the accompanying drawings, in which—

Figure 1 shows a perspective view of a neck protector for draft animals embodying 45 my device. Fig. 2 shows a rear view of the same.

In the accompanying drawings, I have used the reference numeral 10 to indicate the body portion of my device. The body portion 50 55 10 is made in duplicate to fit each side of the neck, and is made to extend from the central line at the top of the neck to the central line below the neck. The upper part of the body portion 10 is comparatively narrow, while the part which covers the shoulder where the tug is usually secured to the

collar is made sufficiently broad to permit movement of the collar without allowing the protector to slip out from under the collar. The body portions 10 are cut to fit the right 60 or left side of the neck, and their upper portions are approximately parallel to each other while the lower broader portions of each side are stretched or otherwise made to lie in planes forming acute angles with 65 the said upper portions, so that the sides of the protector conform approximately to the contour of a horse's neck. The body portions 10 are sewed or otherwise secured to each other at the top. I provide straps and 70 buckles 11 and 12 near the lower end of the body portions 10 for fastening my neck protector, and also for permitting the variation in its sizes to correspond to variations in the sizes of the neck on which the protector 75 is used. I make my neck protector in sizes corresponding to the ordinary sizes of collars. The buckles 10 and 11 are intended to permit regulation of the sizes only to a limited extent. I preferably cut the body 80 portions 10 of such sizes that they will not quite touch each other at the lower end when fitted on a horse. Upon the lower faces of the body portions 10 at their upper end, I provide a broad pad 13 extending some distance downwardly on each side, and extending forwardly and rearwardly from the 85 portions 10.

In constructing the pad 13, I provide a slight upward curve near the forward end 90 of said pad 13 to correspond to the shape of the horse's neck. The pad 13 serves several purposes. By means of its ends which extend laterally from the body portions 10, movement of the lower end of said body portions 10 forwardly whereby the pad might 95 slip out from under the collar is prevented. If the lower ends of the body portions 10 are moved forwardly away from the shoulders of the horse, the forward end of the 100 pad 13 presses against the neck, and the weight of the lower portion of the neck protector serves as a power to draw the protector back into its proper position, the whole protector forming a lever which acts 105 at a point in front of the portions 10, upon the neck of the horse as a fulcrum. The pad 13 also distributes the downward draft over a large area saving the neck from undue pressure at one point. Said pad also serves 110 as a housing to protect the neck from water or the like. For the purpose of strengthen-

ing the neck protector and retaining its proper shape, I provide a reinforcing support 15 at the upper ends of the body portions 10 extending from side to side thereof, 5 and secured thereto. I provide extensions 14 near the lower rear sides of the body portions 10 extending back from said body portions, said extensions serving as pads for the tugs and protecting the horse therefrom.

10 I preferably make my neck protector of leather, but it may be made of other suitable material or of more than one material and kind of leather or other material may be varied as desired.

15 One of the advantages of my invention is that I have combined in a single device, which is wholly independent of the harness, first a means for fully protecting a horse from abrasion, bruising or overheating of 20 the neck and shoulders that is sometimes caused by a collar, second I provide a housing to protect the horse's neck and shoulders from rain or snow and have then dispensed with the use of the housing usually worn 25 over the top of the collar, and third, I have provided a neck pad for the collar to protect the horse's neck and to dispense with

the use of the neck pad usually worn under the top of the collar.

I claim as my invention:

30 A neck protector for draft animals, comprising right and left thick body portions designed to fit respectively the right and left sides of the neck and shoulder of a draft animal and to remain in place without attachment to the collar, said body portions being comparatively narrow at the top and broad enough at the lower end to protect the shoulders of the draft animal from the collar 35 during the ordinary movements of a collar 40 when in use, a thick leather pad secured to the upper ends of said body portions, extending beyond them forwardly and rearwardly and designed to fit the top of a draft animal's neck, said pad being composed of material of sufficient thickness and rigidity 45 to spread the downward draft of a collar over surface materially greater than would be affected in the collar alone.

Des Moines, Iowa, February 20, 1911.
DAVID A. KENT.
